IGNITION SYSTEM AND GENERATOR
THEREFORSidney E. Miller, Suffield, Conn., assignor to
American Bosch Corporation, Springfield,
Mass., a corporation of New York

Application January 28, 1950, Serial No. 140,991

17 Claims. (Cl. 123—148)

1

This invention relates to a new and improved low tension breakerless ignition system for large, relatively low speed engines, and a new and improved generator for said system.

An object of the invention is to provide an ignition system of the type set forth which employs low tension distribution and provides a long duration, multiple spark output.

Another object of the invention is to provide a new and improved generator for an ignition system of the type set forth.

Another object of the invention is to provide a low tension ignition system and a generator therefor, which employ no moving contacts, slip rings, brushes, commutators or other devices which might cause an open arc, and, therefore, is practically explosion proof.

Another object of the invention is to provide an ignition system of the type set forth in which the length of high tension lead may be reduced to a minimum.

Other objects and advantages of the invention will be apparent from the following description taken in connection with the accompanying drawings. It will be understood that changes may be made in the details of construction and arrangement of parts without departing from the scope of the invention as expressed in the accompanying claims, as the preferred form of the invention has been given by way of illustration only.

Referring to the drawings:

Fig. 1 is a diagrammatic view of an ignition system embodying the invention;

Fig. 2 is a longitudinal sectional view of the generator employed in the system;

Fig. 3 is a sectional view taken on line 3—3 of Fig. 2;

Fig. 4 is a sectional view taken on line 4—4 of Fig. 2, looking in the direction of the arrows;

Fig. 4A is an end view of the generator;

Figs. 5 to 7 inclusive are sectional views, on an enlarged scale and illustrating the flux reversal operation of the generator of Figs. 2, 3 and 4; and

Fig. 8 is a plan view of the preformed winding or coil employed in the stator.

Referring more particularly to the drawings, wherein similar reference characters designate corresponding parts throughout, the ignition system is shown by way of illustration only in Fig. 1 as applied to a double or dual ignition engine, but it will be understood that it may also be applied to either double or single ignition engines.

In Fig. 1 there is shown the generator stator

2

10 having the tooth 11 between slots 12 and 13 and on tooth 11 is provided generating winding 14 which is connected at one end by lead 15 to ground 16 and at its opposite end by lead 17 to transformer 18.

15 A rotor 19 is provided which includes a pair of poles 20 and 21 adjacent its periphery and between said poles 20 and 21 is provided a bar shaped permanent magnet 22 which is carried by the rotor 19 for rotation therewith.

Instead of the permanent magnet 22, wound field coils or other means providing a pair of magnetic poles on the rotor capable of providing axial excitation of the rotor could be employed.

20 Between stator 10 and rotor 19, and concentric with said stator is provided inductor or flux reversing ring or rotor 23. This rotor 23 is of squirrel cage form and consists of a series of spaced lamination stacks 24 of electrical sheet steel, each of the stacks being separated from the others by non-magnetic material.

The flux reversing or chopping rotor 23 is preferably rotated in the same direction as rotor 19 and also preferably at about five times the speed 25 of rotor 19 which is driven at engine speed for a two-stroke cycle engine or one-half engine speed for a four-stroke cycle engine, although said flux reversing rotor 23 could be so constructed and arranged as to work satisfactorily while rotating in the opposite direction from rotor 19 or even if not rotated. Also, either the stator 10 or rotor 19 could be stationary instead of rotor 23 or rotated in the same direction or otherwise.

30 The number of teeth 11 and windings 14 which are provided on stator 10 depend upon the number of cylinders in the engine on which the system is employed and the spacing of said teeth 11 and windings 14 can be equal or not as desired for timing of a particular engine although normally such teeth 11 and coils 14 are equally spaced.

35 In the system shown in Fig. 1 for dual ignition, the transformer 18 includes the primary 25 grounded at 26 and a double or two-section secondary winding having the sections 27 and 28 each connected to one of the spark plugs 29 and 30 respectively. In this system the voltage limiting gaps or safety gaps 31 and 32 are provided in the transformer housing.

40 In Figs. 2, 3 and 4 is shown an embodiment of the generator designed for use with an eight cylinder engine. In this embodiment the stator 10 is provided with eight equally spaced teeth 11, each provided with a set of slots 12 and 13 on the opposite sides thereof, each of which slots 45 is lined with an insulating paper and a preformed

50

coil 33 is placed in each set of slots, and one of the leads 34 therefrom is connected to terminal posts 35 and the other lead 36 is connected to ground.

Rotor 19 is mounted on shaft 37 for rotation therewith, which shaft is journalled in bearings 38 and 39 and adapted to be driven by the engine.

Stator 10 is retained in position between end plates 40 and 41 by studs 42.

Ring gear 43 is secured to end plate 40 by bolts or the like 44. Carrying arm 45 is keyed to shaft 37 and supports the two planetary gears 46 and 47 which mesh with ring gear 43 and sun gear 48 which, in turn, is mounted on flux reversing ring 23 which is journalled in bearings 49 and 50 on shaft 37.

Magnet rotor 19 comprises a pair of end plates 51 and 52 pressed on shaft 37 and supporting therebetween bar magnet 22 and counterweight 23. Pole shoes 20 and 21 are also carried by rotor 19. Damper ring 53 surrounds magnet 22.

Flux reversing ring 23 comprises a pair of end plates 54 and 55 which are journalled on the shaft and between which are supported the lamination stacks 24 which each have rivets 56 extending therethrough which rivets have their opposite ends extending through rings 57 and 58 after which the ends of the rivets are headed over and this entire unit is supported by the end plates by screws or the like.

Baffle 59 and oil seal 60 separate the gear compartment from the electrical compartment.

In operation, shaft 37 is driven by the engine and said shaft, in turn, rotates rotor 19 and through the planetary gearing rotates flux-reversing ring 23 as previously described.

The flux-reversing system is shown in detail in Figs. 5, 6 and 7.

In Fig. 5, lamination stack 24a is just approaching but slightly spaced from tooth 11 and lamination stacks 24a and 24b are aligned with pole shoes 20 and 21 of rotor 19. Then the flux will follow the path shown by the arrows in Fig. 5.

As the rotor 19, and pole shoes 20 and 21 move slightly and lamination stack 24a of flux reversing ring 23 moves into alignment with the edge of tooth 11, the flux will pass through lamination stacks 24a and 24b and follow the path shown by the arrows in Fig. 6.

As the rotor 19 and lamination stack 24a of flux reversing ring move slightly beyond the position shown in Fig. 6, the flux will follow the path shown in Fig. 7.

This change of flux path rapidly reverses the flux through tooth 11 between the windings and this rapid reversal of flux produces the potential or output of the generator.

It will be seen from the foregoing that because of the flux reversing ring 23 a more rapid flux reversal is obtained which is necessary for good output at low speeds and that yet only a single magnet is employed.

Also, this system results in multiple spark ignition which is advantageous for the firing of lean mixtures.

Instead of the flux reversing ring 23 as shown in Figs. 5 to 7 inclusive, this ring could be employed as a flux chopping or pulsing unit in which no flux reversal is effected, but instead said ring would vary the flux from zero to a maximum value with constant polarity. In such a construction the rotor 19 will be essentially unipolar and excited either by integral magnets or remote

axial excitation, employing either permanent magnets or wound field coils.

Furthermore it will be noted that the low tension system of the present invention lends itself to complete shielding for making an explosion proof construction for use in installations such as gas fields where combustible materials may be present.

From the foregoing it will be seen that I have provided new and improved means for obtaining all of the objects and advantages of the invention.

Having described my invention, I claim:

1. In a device of the character described, a stator having multiple tooth sections with an intermediate tooth of each section having a generating coil, a magnet rotor having a pair of magnetic poles and a flux reversing ring between said stator and said magnet rotor, said flux reversing ring having at least one pair of magnetic bridges adapted to effect a reversal of flux as rotation is effected between said ring and said stator and rotor.

2. In a device of the character described, a stator having multiple tooth sections with an intermediate tooth of each section having a generating coil, a magnet rotor having a pair of magnetic poles, a flux reversing ring between said stator and said magnet rotor and means for effecting relative rotation between said inductor ring and said magnet rotor and stator, said flux reversing ring having at least one pair of magnetic bridges adapted to effect a reversal of flux as rotation is effected between said ring and said stator and rotor.

3. In a device of the character described, a stator having multiple tooth sections with an intermediate tooth of each section having a generating coil, a magnet rotor having a pair of magnetic poles, means for rotating said magnet rotor relative to said stator, a flux reversing ring between said stator and said magnet rotor and means for rotating said inductor ring relative to said stator, said flux reversing ring having at least one pair of magnetic bridges adapted to effect a reversal of flux as rotation is effected between said ring and said stator and rotor.

4. In a device of the character described, a stator having multiple tooth sections with an intermediate tooth of each section having a generating coil, a shaft, a magnet rotor having a pair of magnetic poles adapted to be rotated by said shaft and a flux reversing ring between said stator and said magnet rotor and adapted to be rotated by said shaft, said flux reversing ring having at least one pair of magnetic bridges adapted to effect a reversal of flux as rotation is effected between said ring and said stator and rotor.

5. In a device of the character described, a stator having multiple tooth sections with an intermediate tooth of each section having a generating coil, a magnet rotor having a pair of magnetic poles and a flux reversing ring between said stator and said magnet rotor, a shaft adapted to rotate said magnet rotor and a planetary gearing rotated by said shaft and adapted to rotate said inductor ring, said flux reversing ring having at least one pair of magnetic bridges adapted to effect a reversal of flux as rotation is effected between said ring and said stator and rotor.

6. In a device of the character described, a stator having multiple tooth sections with an intermediate tooth of each section having a gen-

erating coil, a magnet rotor and a flux reversing ring between said stator and said magnet rotor, and a single pair of magnetic poles on said magnet rotor, said flux reversing ring having at least one pair of magnetic bridges adapted to effect a reversal of flux as rotation is effected between said ring and said stator and rotor.

7. In a device of the character described, a stator having multiple tooth sections with an intermediate tooth of each section having a generating coil, a magnet rotor, a flux reversing ring between said stator and said magnet rotor and means for effecting relative rotation between said inductor ring and said magnet rotor and stator, and a single pair of magnetic poles on said magnet rotor, said flux reversing ring having at least one pair of magnetic bridges adapted to effect a reversal of flux as rotation is effected between said ring and said stator and rotor.

8. In a device of the character described, a stator having multiple tooth sections with an intermediate tooth of each section having a generating coil, a shaft, a magnet rotor adapted to be rotated by said shaft and a flux reversing ring between said stator and said magnet rotor and adapted to be rotated by said shaft, and a single pair of magnetic poles on said magnet rotor, said flux reversing ring having at least one pair of magnetic bridges adapted to effect a reversal of flux as rotation is effected between said ring and said stator and rotor.

9. In a device of the character described, a stator having multiple tooth sections with an intermediate tooth of each section having a generating coil, a shaft, a magnet rotor having a pair of magnetic poles adapted to be rotated by said shaft and a flux reversing ring between said stator and said magnet rotor and adapted to be rotated by said shaft at a speed considerably greater than the speed of rotation of said magnet rotor, said flux reversing ring having at least one pair of magnetic bridges adapted to effect a reversal of flux as rotation is effected between said ring and said stator and rotor.

10. In a device of the character described, a stator having multiple tooth sections with an intermediate tooth of each section having a generating coil, a magnet rotor having a pair of magnetic poles and a flux reversing ring between said stator and said magnet rotor, a shaft adapted to rotate said magnet rotor and a planetary gearing rotated by said shaft and adapted to rotate said inductor ring at a speed considerably greater than the speed of rotation of said magnet rotor, said flux reversing ring having at least one pair of magnetic bridges adapted to effect a reversal of flux as rotation is effected between said ring and said stator and rotor.

11. In an internal combustion engine ignition system, a generator driven by the engine and having a stator having multiple tooth sections with an intermediate tooth of each section having a generating coil, a magnet rotor having a pair of magnetic poles and a flux reversing ring between said stator and magnet rotor, said flux reversing ring having at least one pair of magnetic bridges adapted to effect a reversal of flux as rotation is effected between said ring and said stator and rotor and adapted to produce by the reversal of flux therebetween an output consisting of a group of impulses in rapid succession at each firing period of the engine with a period of substantially zero generation between successive groups of impulses, a transformer having its primary connected to the output terminals of said

generator and a load circuit connected to the secondary of said transformer and including spark gap means for said engine periodically energized by said groups of impulses.

5 12. In a device of the character described adapted to supply ignition pulses to each of the cylinders of an internal combustion engine, a stator having multiple tooth sections with an intermediate tooth of each section having a generating coil and having a tooth or pole and coil for each engine cylinder, a magnet rotor carrying a single pair of magnetic poles and a flux reversing ring between said stator and magnet rotor, said flux reversing ring comprising a plurality of spaced lamination stacks forming magnetic bridges and adapted to reverse the flux path through said stator tooth or pole.

10 13. In a device of the character described adapted to supply ignition pulses to each of the cylinders of an internal combustion engine, a stator having multiple tooth sections with an intermediate tooth of each section having a generating coil and having a tooth or pole and coil for each engine cylinder, a magnet rotor carrying a single magnet and a pair of magnetic poles and a flux reversing ring between said stator and magnet rotor, said flux reversing ring comprising a plurality of spaced lamination stacks forming magnetic bridges and adapted to reverse the flux path through said stator tooth or pole, and means for effecting relative rotation between said stator and magnet rotor.

15 14. In a device of the character described adapted to supply ignition pulses to each of the cylinders of an internal combustion engine, a stator having multiple tooth sections with an intermediate tooth of each section having a generating coil and having a tooth or pole and coil for each engine cylinder, a magnet rotor carrying a single magnet and having a pair of magnetic poles and a flux reversing ring between said stator and magnet rotor, said flux reversing ring comprising a plurality of spaced lamination stacks forming magnetic bridges and adapted to reverse the flux path through said stator tooth or pole, and means for effecting relative rotation between said stator and said flux reversing ring and magnet rotor.

20 15. In a device of the character described adapted to supply ignition pulses to each of the cylinders of an internal combustion engine, a stator having multiple tooth sections with an intermediate tooth of each section having a generating coil and having a tooth or pole and coil for each engine cylinder, a magnet rotor carrying a single magnet and having a pair of magnetic poles and a flux reversing ring between said stator and magnet rotor, said flux reversing ring comprising a plurality of spaced lamination stacks forming magnetic bridges and adapted to reverse the flux path through said stator tooth or pole, and means for effecting rotation of said flux reversing ring relative to said stator and magnet rotor.

25 16. In a device of the character described adapted to supply ignition pulses to each of the cylinders of an internal combustion engine, a stator having multiple tooth sections with an intermediate tooth of each section having a generating coil and having a tooth or pole and coil for each engine cylinder, a magnet rotor carrying a single magnet and having a pair of magnetic poles and a flux reversing ring between said stator and magnet rotor, said flux reversing ring comprising a plurality of spaced lamination

stacks forming magnetic bridges and adapted to reverse the flux path through said stator tooth or pole, a shaft for rotating said magnet rotor and planetary gearing for effecting rotation of said flux reversing ring upon rotation of said shaft.

17. In a device of the character described adapted to supply ignition pulses to each of the cylinders of an internal combustion engine, a stator having multiple tooth sections with an intermediate tooth of each section having a generating coil and having a tooth or pole and coil for each engine cylinder, a magnet rotor carrying a single magnet and having a pair of magnetic poles and a flux reversing ring between said stator and magnet rotor, said flux reversing ring comprising a plurality of spaced lamination stacks forming magnetic bridges and adapted to reverse the flux path through said stator tooth or pole, a shaft for rotating said magnet rotor and planetary gearing for effecting rotation of

said flux reversing ring at a speed considerably greater than the speed of rotation of said magnet rotor.

SIDNEY E. MILLER.
